2,526,963

PROCESS FOR STABILIZING
HYDROCARBONSLloyd C. Morris, Bartlesville, Okla., assignor to
Phillips Petroleum Company, a corporation of
Delaware

Application July 11, 1946, Serial No. 682,765

6 Claims. (Cl. 44—68)

1

This invention relates to the stabilization of hydrocarbons. In one particular aspect it relates to methods of stabilizing hydrocarbon oils against deterioration caused by oxygen and in another particular aspect it relates to novel reagents for preventing such deterioration. In still another aspect it relates to a method of distillation wherein such novel reagents are added to the feed to a distillation process.

It is common knowledge that many hydrocarbon materials, particularly those containing unsaturated compounds, deteriorate when oxygen is present, with formation of gummy substances, oxygenated hydrocarbon derivatives, and in some instances with the development of objectional odors. While such deterioration processes are more common in materials containing unsaturated compounds, some saturated hydrocarbons exhibit the tendency to develop unpleasant odor when heated in the presence of air. This tendency to develop unpleasant odor is especially marked in materials containing substantial proportions of highly branched aliphatic alkylates, similar to the alkylates used extensively in high octane motor fuels, because of the large number of tertiary carbon atoms present in such materials. Often this development of odor is accompanied by the formation of oxygenated hydrocarbon derivatives whose exact structure is not clearly understood but which include aldehydes, ketones, carboxylic acids, the unstable compounds known as peroxides, and the like. Such deterioration frequently renders a hydrocarbon material undesirable for many otherwise valuable potential uses.

Methods for preparing fractions of highly branched paraffin hydrocarbons having substantially no odor are described in copending applications of Legatski and Crawford, Serial No. 616,930, now Patent 2,468,986, filed September 17, 1945; Crawford and Morris, Serial No. 617,870, now Patent 2,463,601, filed September 21, 1945; and Axe, Serial No. 675,531, now Patent 2,523,459, filed June 10, 1946. After preparation of these substantially odorless fractions storage of the product has often been accomplished in containers from which oxygen was excluded by blanketing with a non-oxidizing odorless gas, such as that formed by the method taught in the copending application of Glidden, Serial No. 651,031, filed February 28, 1946. As an alternative for these obviously cumbersome

2

procedures the addition of stabilizers such as phenols and phenolic derivatives have been employed in some instances. However, the intrinsic disagreeable odors of such phenolic compounds has rendered their use objectional in many cases.

It is an object of this invention to provide a method for stabilizing hydrocarbon materials against deterioration caused by oxidation.

Another object is to provide a method for preventing development of undesirable odor in hydrocarbon materials containing substantial proportions of highly branched paraffin hydrocarbons.

Another object is to provide novel oxidation inhibitors capable of greatly reducing or preventing deterioration of hydrocarbon materials by oxidation.

Another object is to provide a method of preparing substantially odorless fractions of highly branched paraffin hydrocarbons.

Other objects and advantages will be apparent to those skilled in the art as this disclosure proceeds.

I have found that deterioration due to oxidation in hydrocarbon materials and particularly in those hydrocarbon materials containing substantial proportions of highly branched paraffin hydrocarbons can be eliminated or substantially reduced by incorporating small proportions of certain high molecular weight organic salts of certain heavy metals therein. I have also found that heating and/or distilling such hydrocarbons can be effected to provide substantially odor free products when one of the oxidation inhibiting agents of this invention is added to the hydrocarbon material and is present during such heating or distillation process.

The novel inhibiting agents of my invention comprise the stannous, ferrous, cobaltous and nickelous salts of high molecular weight fatty acids containing not more than one unsaturated linkage to the molecule, such as the stearates, palmitates, oleates and the like. Particularly I prefer to use the stannous salts of fatty acids selected from the group consisting of the saturated and mono-olefinic unsaturated fatty acids having from 16 to 18 carbon atoms, inclusive, per molecule, of which the stearate, palmitate, and oleate are representative. In the practice of my invention I have generally preferred to operate with stannous stearate as an oxidation inhibitor

because of its more ready availability and because of the preferred color characteristics of the hydrocarbon product containing this inhibitor.

In general under conditions where moderate oxidation is to be expected I prefer to use about 0.05 to 0.10 weight per cent of inhibitor in the hydrocarbon material to be stabilized although as much as 0.5 per cent may be sometimes desirable and under other conditions as little as 0.005 per cent may be effective. The amount to be used will vary somewhat with the degree of heating expected to be encountered, the proportion of oxygen in gases in contact with such hydrocarbon materials, degree of exposure to air or oxygen, etc. In all cases the proportion of inhibitor to hydrocarbon is quite small.

The oxidation inhibitors of my invention may be employed not only to inhibit oxidation in hydrocarbon materials during storage or use but also in distillation processes for the manufacture of substantially odorless fractions of highly branched paraffin hydrocarbons. The attached drawing illustrates diagrammatically a process for preparing such fractions by a method embodying my invention.

Referring thereto, a feed comprising highly branched paraffin hydrocarbons enters via line 1 and is introduced into a medial portion of a conventional fractionation tower 2. From 0.005 to 0.50 per cent of a stannous, ferrous, cobaltous or nickelous salt of a high molecular weight fatty acid having not more than one olefinic bond per molecule is continuously introduced into and admixed with the incoming feed via line 3. Distillation is conducted in tower 2 by methods well known in the art, using reflux. It may frequently be desirable to withdraw the fraction of distillate required as side stream via line 4. Such procedure is indicated when the feed contains odorous materials of slightly greater volatility than the product desired. These may be distilled off overhead and discarded. From 0.005 to 0.50 per cent of an oxidation inhibitor of the type mentioned above are added to the product via line 6. The product is then conducted to stripper 10 where materials boiling below the initial boiling point of the desired product are removed via overhead line 16. The desired product, containing inhibitor is withdrawn via line 11 to storage 12.

When the feed does not contain an appreciable quantity of volatile odorous materials the product may be withdrawn via line 5. The oxidation inhibitor may be added either to the product line or to the product in suitable storage vessels. The portion of the drawing showing the line from the top of tower 10 and the circuit back to the upper portion of the tower portrays a conventional reflux arrangement.

In any event it is frequently necessary to discard a small amount of the initial product which distills while considerable quantities of air are in the apparatus.

A salient advantage of the present invention lies in the simplicity of my process as compared to methods involving blanketing distillation and storage apparatus with inert odorless gas. Other obvious advantages are due to the persistence of the stabilizing effect imparted, the broad field of low cost materials made available for the production of liquid hydrocarbon fractions having low odor intensity, the freedom from intrinsic odors imparted by the inhibitor, and other features which will be apparent to those skilled in the art.

While I have described one particular embodiment of my invention as applied to mixtures of saturated hydrocarbons comprising a substantial proportion of branched chain paraffins, its utility as applied to other types of hydrocarbons susceptible to similar deterioration will be apparent and such application is within the scope of this invention.

Example I

A sample of odor free alkylate boiling between 340 and 400° F. was obtained by distillation in an atmosphere of inert gas. Samples of this alkylate were shaken with air for five minutes after which three portions were stabilized by adding 0.1 per cent by weight of stannous stearate. A fourth was left untreated to serve as a control. The samples were heated under total reflux for varying periods of time. Results of the tests are shown below.

	Inhibitor	Heating Time	Heating Temp.	Odor	Peroxide Content PPM(as H ₂ O ₂)
25	None	None	None	None	0
	Do	15 min	Boiling	Rancid	110
	0.1 part Stannous Stearate	do	do	None	2
	Do	24 hrs	do	do	0
	Do	48 hrs	do	do	3

Example II

The experiment of Example I was repeated employing 0.05 parts by weight of stannous oleate as the stabilizing agent. Conditions and procedure were substantially as before. The results are shown in the following tabulation.

	Inhibitor	Heating Time	Heating Temp.	Odor	Peroxide Content PPM(as H ₂ O ₂)
30	None	None	None	None	0
	Do	15 min	Boiling	Rancid	110
	.05 part Stannous Oleate	do	do	None	0
	Do	180 min	do	do	0

Having described my invention and explained its operation, I claim:

1. The process of preparing substantially odorless fractions of highly branched paraffin hydrocarbon mixtures while avoiding odor formation caused by oxidative deterioration while heating which comprises adding from 0.005 to 0.5 weight per cent of a stannous salt of a fatty acid selected from the group consisting of saturated and monoolefinic unsaturated fatty acids containing from 16 to 18 carbon atoms per molecule to a mixture of highly branched paraffin hydrocarbons, subjecting the resulting mixture to fractional distillation in a fractionating tower heated at the bottom and refluxed at the top, withdrawing a relatively small proportion of overhead containing odorous materials, and withdrawing a distillate from said fractionating tower consisting of a substantially odorless hydrocarbon fraction of desired boiling range.

2. The process of claim 1 wherein said stannous salt is stannous stearate.

3. The process of claim 1 wherein said stannous salt is stannous oleate.

4. The process of claim 1 wherein from 0.05 to 0.1 weight per cent of said stannous salt is added.

5. The process of claim 1 wherein said odorous overhead is continuously withdrawn, and said odorless distillate is continuously withdrawn as a side stream.

6. The process of claim 1 wherein said odorous

overhead is initially withdrawn during the time that residual air is present in the upper portion of said fractionating tower, and said odorless distillate is subsequently withdrawn as an overhead product.

Certificate of Correction

Patent No. 2,526,963

October 24, 1950

LLOYD C. MORRIS

It is hereby certified that error appears in the printed specification of the above numbered patent requiring correction as follows:

Column 1, line 43, for the patent number "2,523,459" read 2,523,549; and that the said Letters Patent should be read as corrected above, so that the same may conform to the record of the case in the Patent Office.

Signed and sealed this 1st day of May, A. D. 1951.
